UNITED STATES PATENT OFFICE

161,084

COMBINED AIR SUCTION AND THREAD TRIMMING MACHINE

Joseph Blaeker, Brooklyn, N. Y.

Application April 25, 1949, Serial No. 2,236

Term of patent 3½ years

(Cl. D55—1)

To all whom it may concern:

Be it known that I, Joseph Blaeker, a citizen of the United States of America, residing in Brooklyn, county of Kings and State of New York, have invented a new, original, and ornamental Design for a Combined Air Suction and Thread Trimming Machine, of which the following is a specification, reference being had to the accompanying drawing, forming part thereof.

Figure 1 is a perspective view of a combined air suction and thread trimming machine, embodying my new design; and

Figure 2 is a view of the opposite end shown in Figure 1.

I claim:

The ornamental design for a combined air suction and thread trimming machine, substantially as shown.

JOSEPH BLAEKER.
